UNITED STATES PATENT OFFICE.

WILLIAM D. KYLE, OF MILWAUKEE, WISCONSIN, ASSIGNOR TO LINE MATERIAL COMPANY, OF SOUTH MILWAUKEE, WISCONSIN, A CORPORATION OF WISCONSIN.

INSULATOR CLEVIS.

Application filed January 10, 1920. Serial No. 350,646.

To all whom it may concern:

Be it known that I, WILLIAM D. KYLE, a citizen of the United States, and resident of Milwaukee, in the county of Milwaukee and State of Wisconsin, have invented new and useful Improvements in Insulator Clevises, of which the following is a description, reference being had to the accompanying drawings, which are a part 10 of this specification.

The present invention relates to certain new and useful improvements in insulating clevises for use in supporting overhead electrical wires, truss wires, or the like, and has 15 for its primary object to provide a novel form of securing strap or yoke member of bendable strip metal substantially U-shape in cross-section.

Another object of the present invention is 20 to provide an insulator clevis of the class described in which the metal yoke or securing members are made of bendable strip steel, whereby the same will, under stress, conform to the shape of the insulating block.

In the clevises of this class now in common use, the bolts employed to secure the yoke members to the insulating block bend after a strain has been applied thereto, and consequently, it is necessary that a line in which 25 the clevis is used must be tightened after a short period of use to accommodate for the slack caused by the bending of the securing bolt.

Hence, a further object of the present 30 invention is to provide an insulator clevis of the class described in which the securing bolts and the openings therefor are curved from the centers toward the direction of strain.

A still further object of the present invention is to provide an insulator clevis of the class described in which the insulating block has two sets of opposed grooves in its sides for receiving the securing straps or yoke 40 members which are formed of bendable, channeled strip steel or the like, whereby the same will, under strain, conform to the shape of the insulating block without liability of chipping the block or may be bent 45 by hand to fit any insulating block.

With the above and other objects in view which will appear as the description proceeds, my invention resides in the novel construction, combination and arrangement of 50 parts substantially as hereinafter described

and more particularly defined by the appended claims, it being understood that such changes in the precise embodiment of the herein disclosed invention may be made as come within the scope of the claims.

In the accompanying drawing I have illustrated one complete example of the physical embodiment of my invention constructed according to the best mode I have so far devised for the practical application of the 60 principles thereof, and in which:

Fig. 1 is a plan view of an insulator clevis constructed according to and embodying the various features of my invention.

Fig. 2 is a transverse sectional view there- 70

through taken on the line 2—2 of Fig. 1, and Fig. 3 is a longitudinal sectional view taken therethrough on the line 3—3 of 75

Fig. 1.

Referring now more particularly to the accompanying drawing in which like reference characters designate like parts throughout the several views, the numeral 5 designates a block of insulating material, such as porcelain, fiber, or the like, which is substantially cylindrical, and has two sets of opposed grooves or channels 6 and 7 in its side walls for receiving the ends 8 of suitable substantially U-shaped securing or yoke members 9 and 10, to be later described.

As best shown in Figures 2 and 3, the grooves 7 are connected together near one end by means of an opening 11 curved from its center toward the other end of the block and the grooves 6 are connected together by 80 means of an opening 12 also curved in a direction opposite to the curvature of the opening 11. The members 9 and 10 are of substantially U-shape and have their outer closed ends of less diameter than the distance 85 between their open ends for engagement with the cable, wire or the like, with which they are employed; and have their inner surfaces rounded to prevent the cutting of the wire or cable with which they are used when 90 strain is applied thereto. As the members 9 and 10 are formed of bendable channeled strip material U-shaped in cross section, they are normally provided with the desired 95 curvature, as described.

The members 9 and 10 are arranged with their closed end extended in opposite directions and their open ends secured in the grooves 7 and 6, respectively, by fastening bolts 13. The bolts 13 are also curved, as 100

105

110

best shown in Figures 1 and 2, and their curvature is from their centers toward the closed end of the yoke member with which they are employed, or, in other words, their curvature is in the direction of strain. Were the bolts 13 to be straight, they would normally bend after being subjected to a strain for any period of time and thus damage the ends of their opening and necessitate the tightening of the cables or wires with which the clevis is used to accommodate for the slack caused by the bending of the bolts. By my structure, I anticipate this bending of the bolts 13 and thus when the clevis is placed in a line it is not necessary to again tighten the line after the clevis has been used a short time.

The bolts 13 are locked in position by means of the usual nut 14 and flat and lock washers 15 and 16. As before stated, the members 9 and 10 are made of bendable strip material so that they will conform to the shape of the insulator when under strain, and may be readily bent by hand to fit the insulating blocks 5 of various sizes.

From the foregoing description taken in connection with the accompanying drawing, it will be readily apparent to those skilled in the art to which an invention of this character appertains that I provide an insulating clevis embodying a novel form of strap which will be practical for the purposes described.

What I claim as my invention is:

35 1. An insulating clevis of the class de-
scribed comprising an elongated block of
insulating material having two sets of op-
posed channels in the block, the channels of
each set being connected by a transverse
40 opening, the opening of one set being adja-
cent one end of the block and the opening of
another set being adjacent the other end of
the block and at right angles to the other
opening, a pair of U-shaped yoke members
45 of U-shape in cross section and each having
their ends disposed in one set of the chan-
nels, and fastening bolts passed through
said yoke members and openings in the
block.

50 2. An insulating clevis of the class de-
scribed comprising a block of insulating ma-
terial having two sets of opposed channels
in the block, the channels of each set being
connected by a transverse opening, the open-
55 ing of one set being adjacent one end of the

of block and the opening of another set being adjacent the other end of the block and at right angles to the other opening, a pair of like yoke members each having their ends disposed in one set of the channels, and fastening bolts extending transversely through said yoke members and openings in the block, each fastening bolt being curved at its center in its direction of strain.

3. An insulating clevis of the class described comprising a block of insulating material having two sets of opposed channels in the block, the channels of each set being connected by a transverse opening, the opening of one set being adjacent one end of the block and the opening of another set being adjacent the other end of the block and at right angles to the other opening, a pair of like U-shaped yoke members of U-shape in cross section and each having their ends disposed in one set of the channels, said yoke members being shaped to conform with said channels and being substantially bendable, and fastening bolts passed through said yoke members and openings in the block. 70 75 80

4. An insulating clevis of the class described including a block of insulating material having channels in its opposite side walls and an aperture therein near one end connecting the channels, a substantially U-shaped yoke member having its open ends disposed in said channels with its closed end adjacent the end of the block remote from the opening therein, and a fastening bolt passed through apertures in said yoke member and the opening in the block, said block opening and said fastening bolt being curved from their centers toward the closed end of said yoke member, and said yoke member being formed of bendable channeled metal whereby the same will, when under stress, conform to the shape of the block. 85 90 95

5. A clevis of the class described including a flexible U-shaped securing strap formed to engage the opposite sides of an insulating block and having transverse end openings, the strap portions also being of U-shape in cross section, and means extending through the end openings for attaching the end portions of the strap to a block, said block having longitudinal grooves of curved formation in cross section and into which grooves the straps extend. 100
105

In testimony whereof, I affix my signature.

WILLIAM D. KYLE.
